UNITED STATES PATENT OFFICE.

THEODOR H. WEINHAUS, OF ST. CLOUD, MINNESOTA.

MECHANICAL TELEPHONE.

SPECIFICATION forming part of Letters Patent No. 355,363, dated January 4, 1887.

Application filed July 6, 1886. Serial No. 207,196. (No model.)

To all whom it may concern:

Be it known that I, THEODOR H. WEINHAUS, a citizen of the United States, residing at St. Cloud, in the county of Stearns, State 5 of Minnesota, have invented certain new and useful Improvements in Telephones, of which the following is a specification, reference being had therein to the accompanying drawings.

My invention relates to improvements in 10 telephones of the class known as "mechanical telephones;" and the object of my improvements is the construction of a device that will increase the efficiency and the volume and quality of sound transmitted and received by 15 said telephones. I attain these objects by the construction illustrated in the accompanying drawings, in which—

Figure 1 is a central section of a telephone constructed in accordance with my invention. 20 Fig. 2 is a perspective view of the diaphragm formed of two thicknesses of parchment, and showing one of the layers as broken away.

The case consists of two parts, A and B, each composed of a single piece or block of 25 wood suitably turned, as hereinafter described, between which is stretched and clamped the diaphragm D, consisting of two thicknesses, d^1 and d^2 , of parchment. The rear part, A, has a large central cavity on both sides, and between these 30 cavities a thin flat partition is retained to form the sounding-board a . The front portion of the back block, A, is turned out or recessed at A' , adjacent to its periphery, to form an annular shoulder, A^2 , adjacent to its central 35 cavity, A^3 , and upon this shoulder the two parchment thicknesses of the diaphragm D are stretched, after having been suitably dampened, by forcing upon their edges the front ring, B, of the case, the rear face of said ring 40 being suitably recessed and shouldered at B^2 to correspond and interlock with the annular shoulder and recess upon the back block, A. By this interlocking of the surfaces two circular creases and bends, d^2 and d^3 , at right angles 45 to each other, are formed in the diaphragm, that effectually prevent its relaxation or giving way at the edges. The parts A and B are then united by wood-screws c .

The diaphragm has a small perforation, d^4 , 50 in the center, for the passage of the wire E, and upon the front thereof is placed the hard-rub-

ber button e , to which the telephone-wire is fastened, either by twisting its ends or by any suitable wire-holder. The sounding-board is centrally perforated at a^2 for the free passage 55 of the wire E. By this construction a sounding-chamber is produced between the diaphragm and the flat sounding-board. A conical funnel or cavity, A^4 , having its smallest end toward said sounding-board, is made in the 60 rear of the back block, A, and thus while the volume of sound is intensified the ordinary ringing noise is mostly avoided by having the diaphragm constructed of two thicknesses of the same homogeneous substance having the 65 properties of parchment.

I am aware that diaphragms for telephones have been made of one thickness of parchment combined with one or more thicknesses of wood veneer, and also of two thicknesses of 70 parchment separated by one or more thicknesses of fabric or rubber, and also of one thickness of rawhide, combined with a paper disk, and I do not claim any compounds of this nature.

When it is desired to check the humming sound coming over the wire, or to deaden the sound to all but the operator, the sound-waves are controlled by means of a plunger, F, set 75 radially in the rear block of the case behind the sounding-board, and having its outer end projecting from said case and provided with a button, f , that can be pressed upon by the operator. The inner end of the plunger carries a knob, F' , covered with felt or other yielding substance, and is adapted to be pressed with more or less force against the transmitting-wire E; but to permit a loud call the plunger is normally maintained away from the wire by a spring, g , coiled around the 80 plunger and having its outer end bearing against the under side of its button f . A shoulder or collar, f^2 , is placed upon the plunger and is made to abut against the peripheral wall of the conical cavity A^4 of the 85 case, to prevent the plunger from springing back too far from the wire.

Having now fully described my invention, I claim—

1. In combination with the annular blocks 100 A and B, a telephone-diaphragm consisting of two flexible disks, d^1 and d^2 , of the same material,

secured in juxtaposition, substantially as and for the purpose described.

2. In combination with the front block, B, of a telephone and the diaphragm consisting of 5 two disks of the same material stretched in the rear thereof, the rear block provided with a flat perforated sounding-board having its sides parallel with the diaphragm, and in the rear of said sounding-board a conical cavity 10 having its small end abutting against said sounding-board, substantially as and for the purpose described.

3. In combination with the rear block, A, of a telephone-case and its wire, the plunger F, having a yielding knob adapted to bear upon 15 said wire, and a spring to retract it, substantially as described.

In testimony whereof I affix my signature in presence of two witnesses.

THEODOR H. WEINHAUS.
